(57) CLAIM

The ornamental design for a flag with interchangeable detachable appliqués, as shown and described.

DESCRIPTION

A visually appealing flag with interchangeable detachable appliqués.

FIG. 1 is a front view showing my new design with one of the appliqués;

FIG. 2 is a rear view thereof;

FIG. 3 is a top view thereof;

FIG. 4 is a bottom view thereof;

FIG. 5 is a left side view thereof;

FIG. 6 is a right side view thereof; and,

FIG. 7 is a perspective view of my design showing the whole set of appliqués.

The drawings are shaded with stippling to indicate contrasting color and/or texture. The dashed lines represent stitching or a surface treatment resembling to stitching.
